ABSTRACT OF THE DISCLOSURE

A platen press in which a tool holding frame is introduced between the upper and lower platens of the press and is secured to the upper platen in a predetermined position so as to operate on sheet material fed between the platens. The tool holding frame is centered in said predetermined position by means of an extensible element mounted on the upper platen and received in a hole in the tool holding frame, a member being movable with the extensible element for permitting operation of the press only if the frame is centered and said member does not contact the frame.

Brief summary of the invention

The invention relates to platen presses having a fixed platen and a movable one adapted for processing sheet material such as paper or cardboard, for the purpose of cutting, punching, or corrugating the sheet material. Each of the platens is fitted with a frame for the processing of the sheet material. The frame for the upper fixed platen is a tool holder and it supports the tools which process the sheet material, while the frame on the lower movable platen is a counter-plate.

It is indispensable that these frames occupy an accurate predetermined position and that they are protected against any damage likely to arise from a wrong manipulation, in particular an untimely starting of the press, when the frames are not in proper position. This is particularly important with respect to the tool holding frame.

The principal object of the present invention is to provide a device insuring the centering of the tool holding frame, as well as its protection against the consequences of improper handling.

The invention also contemplates the centering of the counter-plate cooperating with the tool holding frame.

The first objective is achieved by an arrangement wherein the tool holding frame comprises at two opposite edges, means insuring a predetermined position thereof in relation to an element fixed with the upper platen and including for one of said edges, a frame housing adapted to accommodate an axially movable centering member integral with the platen and associated with a mechanical part accompanying it in its travel with the object of being placed in the trajectory of the frame, but immediately outside the latter when the frame is in centered position, the centering member being operated by a pressure fluid acting simultaneously on the press, said centering member being effective to impede starting of the press as long as said member is not in a locking position of the frame in its centered position.

In this position, the pressure fluid may simultaneously be utilized for the application and maintainence of the centered frame against the platen.

This maintainence may be by mechanical means, or by a combination of mechanical means and pneumatic means and wherein in the latter case, the centered frame is mechanically urged against the upper platen and at the same time is subjected to a suction pressure between the frame and platen.

2

It is also possible according to the invention to center and secure the counter-plate to the other platen by similar means, with the exception of the mechanical part accompanying the platen and passing on the outside of the frame section, due to the fact that the counter-plate rests on the lower platen.

The assembly of the centering, fixation and safety means of the two frames may be controlled by a hydraulic circuit according to the invention.

10

Brief description of the drawing

FIGURE 1 is a diagrammatic view, in perspective, illustrating a portion of a press showing the problem to be solved in positioning a tool holding frame relative to the upper fixed platen of the press;

FIGURE 2 is a side view, in elevation, of a portion of the press showing a centering device for the tool holding frame in inoperative position;

FIGURE 3 shows the tool holding frame in locked and centered position;

FIGURE 4 is a diagrammatic illustration of a hydraulic control for the centering device;

FIGURES 5 and 6 are views similar to those of FIGS. 2 and 3, showing some features of the device;

FIGURE 7 is a diagrammatic illustration similar to that of FIG. 4, but with the addition of a device for clamping the frame against the platen;

FIGURE 8 is a detailed perspective view to a larger scale of a part of the tool holding frame;

FIGURE 9 is a view in elevation of a portion of the movable lower platen and of centering means of a counter-plate lying on the latter; and

FIGURE 10 is a diagrammatic illustration of the centering and fixation means of the tool holding frame and the counterplate, and safety means adapted to protect these two members from untimely starting of the press, should they be incorrectly placed.

Detailed description of the invention

In FIG. 1 are seen the upper platen 1 and the lower platen 2 of a press. A tool holding frame 3 is introduced between the platens and secured to one thereof in a fixed predetermined position relative thereto.

The upper platen 1 moves up and down in relation to the movable platen 2, and it is contemplated that the upper platen will receive the tool holding frame 3.

The frame 3 is provided with suitable means at its opposite sides so as to allow centering with respect to platen 1.

The frame 3 is inserted between the platens in the direction of the arrow 4, the front side of the frame 3 having a fork-like projection 5. The projection 5 is adapted to cooperate with a rod which is solid with the platen 1 and which serves to center the front side of the frame laterally, without influencing its position in the inserting direction. The rod is not shown, but it is inserted into the fork of projection 5 without clearance. Opposite the fork 5, the frame 3 has a lug 6 with a hole 7.

The platen 1 supports a stem 12 in axially movable position so that the stem 12 may be inserted into the hole 7. This engagement of stem 12 in hole 7 combined with the engagement of fork 5, will guarantee a predetermined position of the frame 3 in relation to the platen 1.

This disposition is represented in FIGS. 2 and 3. In FIG. 2 the frame 3 is represented in dashed and dotted line in the course of being introduced between the platen, whereas in FIG. 3 the frame 3 has been introduced between the platen and centered.

Fixed to the platen 1 is a cylinder 8, containing a piston to which a rod 9 is secured. Rod 9 supports an angle member 10 having a small leg fixed to rod 9 and extending in a plane perpendicular to the rod, whereas the long

Appl. No. 3

leg of member 10 extends parallel to the cylinder axis.

The small leg is adapted to contact the head 11 of the stem 12 which is guided in a block 13 integral with the platen 1. The stem 12 is subjected to the action of a draw-back-spring, tending to lift the head 11 and thereby the stem 12 in the direction of the cylinder 8.

In the inoperative position of the stem as shown in FIG. 2, the stem 12 and the long leg of the angle member 10 are outside the path of the frame 3, which can be freely introduced under the platen 1 in the direction of the arrow 4.

When the frame 3 is introduced beneath platen 1, a pressure fluid, such as air or oil, is admitted in the cylinder 8, so as to push the piston therein in the direction of the head 11 and obtain the position shown in FIG. 3 in which the slightly conical lower end of the stem 12 is introduced into the hole 7 of the lug 6, so as to guide the frame 3 and to complete the centering thereof. In this position, the long leg of the member 10 passes adjacent the lug 6 without contacting it.

The illustration in FIG. 4 shows how the device described is utilized as a safety device, allowing the starting of the press only when the frame 3 is centered.

In this respect, the fluid acting on the piston of cylinder 8 arrives through a conduit or pipe 14. A second conduit 15 extends laterally from the cylinder 8 and is connected to a small cylinder 16.

The conduit 15 is located in cylinder 8 so that the piston therein normally blocks conduit 15, but exposes it when the frame 3 has been centered by the extension of rod 9. At that moment, the fluid acts also on the piston of the small cylinder 16 and brings about the closing of a switch 17 in a supply circuit 18 for the press, such that the press will operate only when there is fluid under pressure in the conduit 15.

The control illustrated in FIG. 4 has been considered to be operated hydraulically; however, it could also be pneumatic. Moreover, the control can be electrically operated through the use of electromagnets and relays for instance.

The angle member 10 also serves the function of an additional safety device, as explained with reference to FIGS. 5 and 6.

In FIG. 5, the frame 3 is assumed to be only partly introduced in the press. In this case, the press should not be allowed to start. This is made possible by the fact that the stem 12 abutting against the frame 3 prevents the lowering of the rod 9, so that, as shown in FIG. 4 switch 17 remains open and the press cannot be operated.

In FIG. 6, the frame has not yet been introduced into the press. It is desirable to be able to run the press at no load, while making sure that the frame 3 is not introduced therein during the running. In order to start the press it is sufficient to place the cylinder 8 under pressure and thereby lower the angle member 10 which, as shown in FIG. 6, prevents passage of the frame 3 between the platen.

Once the frame 3 has been correctly positioned between the platen, it is necessary to secure it in place and maintain it in secured position.

FIGS. 1 and 7 show how this operation can be performed by means of catches or hooks 19 operated by pistons moving in cylinders 20, fixed to the platen 1 and receiving fluid under pressure through conduits 21. The cylinders 20 are fed with pressure fluid from conduit 14 under the control of cylinder 8 via conduits 15 and 21. Thus, it is possible to feed the cylinders 20 with pressure fluid at the same time that cylinder 16 is activated to close switch 17.

FIG. 8 shows stops or tappets 22 adjoining the lug 6 of the frame 3. The stops 22, cooperate for instance, with the platen arris, to fix the position in which the stem 12 can be inserted into the hole 7.

Since one press can accommodate different tools, i.e., different frames 3, these will be of similar size and a

mounting gauge will be used to reproduce the centering conditions of the press for their preparing and starting.

A counter-plate 24 on the lower platen 2 will be centered by means similar to those described hereinabove with respect to the frame 3 and the upper platen 1. For example, as shown in FIG. 9, the counter-plate 23 is disposed above plate 2 and the front part of the counter-plate will be shaped like the frame of FIG. 8, except for stops 22. The counter-plate has a lug 24 with a hole in which can be inserted a centering rod 25 solid with a piston moving in the cylinder 26, itself fixed to the platen 2. The piston is driven by fluid under pressure from conduit 27. The pressure fluid can flow through the conduit 28 when the piston has reached the centering position of the counter-plate, with the aim, as previously described, to act on auxiliary fixation means for the counter-plate and thereby secure the counter-plate 23 to lower platen 2.

As a safety measure, the cylinder 26 and its piston will be of insufficient strength to lift the counter-plate 23. Thereby, it is not possible for the piston to raise a non-centered counter-plate and allow the starting of the press without the counter-plate being in proper working position.

On the opposite side of the lug 24, the counter-plate 25 will be guided exactly as shown in FIG. 1 for the tool holding frame, i.e. by means of a fork such as 5 and a guiding rod. The counter-plate can also be guided by stops integral with the platen for stopping the counter-plate in proper position.

There is diagrammatically represented in FIG. 10 a control circuit by which the centering and fixation of the tool holding frame and the counter-plate can be carried out together and with complete safety. The reference numbers herein refer to the same elements as in the figures previously described.

In operation, when valve 29 is opened, a source of fluid 30 under pressure is put into communication with the cylinder 8 through conduit 14. The stem 12 is displaced and the frame 3 is centered by the insertion of stem 12 into hole 7. When the stem 12 is displaced, the corresponding piston uncovers the conduit 15 and the fluid under pressure passes through conduit 21 and feeds the cylinders 20 whereby the frame 3 is urged against the platen by means of catches or hooks 19 as previously described. At the same time and through cylinder 16 and switch 17, a portion 18 of the press supply circuit is closed.

The closing of the entire press supply circuit however, depends, and as it will appear later, on the simultaneous closure of the two other safety circuits 18' and 18''.

When the cylinder 16 receives fluid, another cylinder 31 also receives fluid. The corresponding travel of its piston brings about the closing of the feeding circuit 32 of a motor 33, which starts the operation of a vacuum pump 39.

Through a conduit 35, this pump acts on suction or vent apertures 36, arranged in the upper platen, to suck and flatten the tool holding frame against the bed of platen 1. At the same time, the vacuum pump brings about the closure of the circuit 18' through cylinder 37.

Thus, the tool holding frame 13 is centered and immobilized and the two controlling circuits 18 and 18' are closed, 18'' still being open. The press therefore cannot be started.

On the other hand, when the valve 38 is opened, fluid under pressure will be sent to the cylinder 26 through the conduit 27. The piston rod 25 then centers and locks the counter-plate 23, as previously described. The movement of the piston in cylinder 26 brings about the feeding of conduit 28 leading to the cylinder 39, the piston of which causes the closure of the circuit 18'' through switch 40.

Thus, only when all the tools are in place and centered will the controlling circuits 18, 18' and 18'' be closed and thereby allow operation of the press.

If one of the pistons of the cylinders 8 or 26 is not shift-

ed to a centering position, one or the other of the circuits 18 and 18' remains open and the starting of the press is prevented.

The described arrangement thus insures an obligatory correct positioning of the tool assembly and the perfect application of the tool holding frame against the bed of the movable upper platen.

Finally, it is obvious that the arrangements adopted are also applicable to a press whose upper platen would be movable and the lower fixed, and even for two platens simultaneously movable.

What is claimed is:

1. A platen press having upper and lower platens and adapted for receiving a tool holding frame and a counter-support frame between said platens for the performance of an operation on a sheet of material, said press comprising means for positioning the tool holding frame in a predetermined location with respect to one of said platens, the latter means including a centering element secured to said one platen and axially movable between a retracted inoperative positioning and an extended operative position in which it can engage the tool holding frame in said predetermined location, and means for operating said centering element and including a member movable therewith so as to be in the path of movement of the tool holder frame but out of contact therewith when the tool holding frame is in said predetermined location and the centering element is extended, the latter said means being operative to enable operation of the press only if said centering element is in extended position and the movable member fails to contact the tool holder frame.

2. A press as claimed in claim 1 wherein said tool holding frame has opposite ends and is provided with a hole at one end for receiving the centering element in its extended position.

3. A press as claimed in claim 2 wherein said tool holding frame includes a guide fork at the other of the ends thereof adapted for engaging, without play, a guide member integral with said one platen.

4. A press as claimed in claim 1 wherein said member which is movable with the centering element is dimensioned so as to prevent extension of the centering element if said member contacts the tool holder frame, whereas once said centering element is extended, the said member will be in the path of movement of the tool holder frame so as to prevent its insertion between the platens should it be disposed outside of said platens.

5. A press as claimed in claim 1 comprising means coupled to the means operating said centering element for holding the tool holding frame against said one platen when the centering element is in extended position.

6. A press as claimed in claim 5 wherein said means for operating said centering element comprises a cylinder fixed to said one platen, and a piston in said cylinder for driving the centering element, said movable member being

secured to said piston, a conduit for the supply of pressure fluid to said cylinder, normally open switch means for controlling the operation of the press, and a second conduit coupled to the cylinder and to the switch means and the means for holding the tool holding frame against said one platen, said piston blocking the passage of pressure fluid to said second conduit until said piston is in a position in which the centering element is extended in operative position at which time the pressure fluid closes said switch means and activates the means for holding the tool holding frame against said one platen, whereby simultaneously the press is started and the tool holding frame is held against said one platen.

7. A press as claimed in claim 1 comprising means on the other of the platens for engaging the counter support frame in a predetermined position relative thereto.

8. A press as claimed in claim 7 wherein the means for engaging the counter support frame comprises a device operated by fluid pressure, and fluid pressure operated switch means for controlling operation of the press, the latter switch means normally being open and coupled to said device, for being supplied with fluid pressure to close the switch means when the counter support frame is in said predetermined position.

9. A press as claimed in claim 8 wherein said means for engaging the counter support frame comprises a piston operated by said device operated by fluid pressure, said counter support frame having a hole in which said piston is received when the counter support frame is in said predetermined position, said device which is operated by fluid pressure having a strength which is sufficiently low so as to be unable to lift the counter support frame with said piston should the latter be misaligned with said hole therein.

10. A press as claimed in claim 1 comprising suction means, operated by the means which operates the centering element, for applying the tool holding frame against said one platen when the latter frame is in said predetermined position and the centering element is in operative position.
